(57) **CLAIM**

The ornamental design for an electrically propelled surfboard, as shown and described.

DESCRIPTION

FIG. 1 is a rear perspective view of an electrically propelled surfboard for according to the principles of the present invention.

FIG. 2 is a top perspective view of the electrically propelled surfboard of FIG. 1.

FIG. 3 is a bottom view of the electrically propelled surfboard of FIG. 1.

FIG. 4 is a top view of the electrically propelled surfboard of FIG. 1.

FIG. 5 is a front view of the electrically propelled surfboard of FIG. 1.

FIG. 6 is a rear view of the electrically propelled surfboard of FIG. 1.

FIG. 7 is a right side view of the electrically propelled surfboard of FIG. 1.

FIG. 8 is a left side view of the electrically propelled surfboard of FIG. 1; and,

FIG. 9 is a bottom perspective view of the electrically propelled surfboard of FIG. 1.
